COIN-TESTING APPARATUS

Application filed May 20, 1929. Serial No. 364,535.

This invention relates to improvements in fraud prevention means for coin actuated mechanism, and particularly to coin testing apparatus adapted for use with vending machines. The general purpose of the invention is attained in the automatic rejection of slugs, blanks and the like, which may be attempted to be used for the fraudulent operation of any usual type of coin actuated mechanism.

An object of the present invention is to provide an improved device entirely of a mechanical nature, which is simple, compact, economical in manufacture, and which will automatically reject from the operative portions of the mechanism to which it is applied, all counterfeit pieces attempted to be substituted for standard coins, in the operation of such mechanism.

A further object of the invention is to provide a device of the class designated, of such a compact and inexpensive type, that it can be applied to a coin actuated mechanism, either at the time of manufacture thereof, or which may be applied, as an accessory, to coin actuated mechanism already in use.

A further object of the invention is to provide a device for the purpose recited, which is susceptible of adjustment and regulation according to the physical characteristics of the coin intended for operating the machine to which it is applied.

A still further object of the invention is attained in a novel form of coin-testing device, for an advance determination of certain physical characteristics of the coin or operating element, by the subjection of such element to a steady pressure, as distinguished from an impact or blow apt to result in a defacing action on the regulation coins employed with the machine.

Further objects and advantages of the invention will appear from the following detailed description, taken in connection with the accompanying drawings in which:

Fig. 1 is a top or plan view of the device; Fig. 2 is a side elevation of the device; Fig. 3 is a section along line 3-3 of Fig. 1; Fig. 4 is an elevation of the under side of

the device; Figs. 5 and 6 indicate certain cam portions formed respectively on the lower and upper mating members of the coin carrier, Figs. 5 and 6 being taken respectively along lines 5-5 and 6-6 of Fig. 3, and Figs. 7, 8, 9 and 10 are diagrams showing respectively, different relative positions of the parts of the coin carrier, to illustrate its operation.

As will be apparent from the following description, the present invention does not intend to cover the mechanism of a vending machine or other usual coin actuated mechanism, but the purpose of the present invention is limited to the rejection of improper actuating elements for such a machine, such as the slugs or blanks often attempted to be employed in place of regulation coins. The present device, however, includes a rotating shaft, for actuating purposes, which shaft may be extended or connected for the purpose of actuating the usual mechanism of certain known types of vending machines.

It will be understood that the present invention is described, in detail, by reference to a specific, presently preferred embodiment, and that the following description of the example is to be considered in an illustrative and not in a limiting sense, since it is obvious that various modifications may be made in the location and arrangement of parts, as well as in the various combinations thereof, without departing from the spirit and full intended scope of the invention, as defined by the appended claims.

By way of providing a preliminary explanation of the principles utilized, it may be indicated that the invention involves subjecting to a steady pressure, the coin or slug introduced for operating the vending mechanism, resulting in a bending or shearing stress which is adjustable in degree, so that, for example, a five cent piece will just resist, without deflection or distortion, the bending pressure applied thereto. After having been subjected to this bending tendency, the coin or slug is carried between the opposed, oppositely presented cam surfaces, of a carrier; the cam surfaces being formed on separate elements which are resiliently

maintained in coacting relation, with the cam surfaces adjacent each other. The elements of the carrier, including those portions upon which the cam surfaces are formed, are so constructed as barely to accommodate, without friction thereon, a coin intended to operate the mechanism with which it is used. If a slug of greater thickness than, say a five cent piece, is inserted and has resisted the bending pressure, this thickness will cause it to be frictionally retained between the cam member in a manner to result in a predetermined abnormal length of travel within the carrier to cause its discharge at a point other than the coin receiving slot of the vending mechanism. Coins of lesser thickness than the ones intended for normal use are, in practically all cases, distorted under the bending influence of the previous operation of the machine, so that their effective thickness is substantially greater than that of the coin for which the vending mechanism is designed. For brevity and a better understanding of the parts and operation of the present apparatus, the action of a coin or slug will be described in its course through the device, along with the description of parts of the machine. For further convenience of description, the present disclosure is directed to a machine intended normally to receive and pass a five cent piece, although it will be understood that the same apparatus may be employed, by slight adjustment and minor modifications, in connection with a vending machine or the like which may be adapted for one cent pieces, quarters or any other standard coin.

Referring now by numerals to the drawings, it will be seen that the device is provided at one end with a coin receiving slot 10, which is by preference, of a width barely in excess of the diameter of a five cent piece; thus this slot of itself, forms a means of rejecting at the outset, any slug of appreciably greater diameter than the coin intended to be used in the vending device. A coin inserted in the slot 10 falls by gravity to a position where its lower edge rests against a cam member 11, (best seen in Fig. 3). At this point the device is actuated, by manually rotating a handle 12, thus rotating in the same direction, a shaft 13, to which the handle 12 is affixed. In the example shown, the shaft 13 rotates clockwise, as viewed in Fig. 3. Formed integrally upon the shaft 13 or secured thereto is a cam 14, the nose of which is adapted, upon rotation of the shaft 13, to impinge upon an inner cam surface of a hook or crank 15, to result in an outward movement of the hook 15. This hook is pivotally secured, as by a through pin 16, to a bridge portion 17, which is provided with sliding journals 18 (Fig. 2) and arranged for a limited reciprocating

movement along one or a plurality of studs such as 19. Extending between, and slideable along the recited studs 19, is a bridge member 20; and between the bridges 17 and 20, is disposed a relatively heavy, or stiff, coil spring 21, which in the present example is arranged concentrically with a plunger 22. Also associated with, and by preference concentrically disposed upon, the studs 19, are a pair of springs 23, which are employed to assist in the return movement of the unitary cross-head or rack structure constituted by the bridge portions 17, 20, and other related elements. Upon movement of the hook 15, as indicated above, the rack structure, including the members 17 and 20 will move, say to the right in Fig. 3, with the result that the plunger 22 will be moved steadily against the central portion of the coin or slug previously deposited in the slot 10. In the frame of the machine there is formed a depression or pocket, such as 24 (Fig. 3), which serves to remove from about the central portions of the coin, any reinforcement against the pressure of the plunger 22, whereby the coin or slug is subjected to a centrally applied shearing or bending force. It will be seen from the shape of the cam 14, and the cam engaging surfaces on the hook 15, that the movement of the plunger will be steady, and progressively outward, or to the right in Fig. 3, with the result that the coin in slot 10 is subjected, not to a pronounced impact, but rather to a steady, but substantial pressure. The width of slot 10 at this point is sufficient to permit the element, if it is so constructed, to be somewhat distorted under the action of the plunger; and if the element be formed of lead, sheet brass, or the like, it will undergo such distortion. If a good coin is employed, its strength is such that no appreciable distortion can occur under the influence of plunger 22. In order that the action of the device will not result in any defacing action on a regulation coin, and in order to maintain the effective pressure of the plunger 22, at a safe maximum, it is necessary to provide for adjustment of the force or pressure applied to the coin. This adjustment is accomplished, in the present example by means of a pair of threaded studs 25 secured into the bridge member 20 and having their threaded portions extending through the bridge member 17, an adjustable distance determined by the setting of nuts 26. It will appear from Figs. 1 and 3 that the plunger 22 is arranged for reciprocal movement with respect to the bridge 17, hence the force or pressure applied either to a coin or slug in the slot 10, will be proportional to the initial compression given the spring 21, as determined by the proper adjustment of the nuts 26 on the studs 25. In practice the spring compression is so lim-

ited that the intended coin will pass the slot 10, without any appreciable distortion or deflection.

By way of further explanation of arrangement and operation of a device, such as appears in Fig. 3, it may be noted that the spring 21 is positioned at its ends by a collar 27, disposed adjacent to bridge member 17 and bearing thereagainst, and a collar 28, disposed adjacent the bridge member 20. The collar 27 is preferably freely movable along the plunger 22, while the portion 28 may be, and is by preference, formed integrally with the plunger, but may be otherwise secured thereto as by a through pin, or the like, (not shown). Upon taking up the nuts 26, for adjusting purposes, the collars 27 and 28 are drawn closer together with the effect of compressing the spring 21. Since the collar 27 is movable along the plunger, it will be seen, as from Fig. 3, that the pressure imparted to the plunger, due to the actuation of cam 14, hook 15 and the bridge member 17, is directly proportionate to the compression of the spring 21, as determined by its adjustment.

While the hook 15 and cam 14 are preferably constructed as indicated in Fig. 3, it will be understood that any suitable equivalent of this driving arrangement may be employed, for example, an eccentric carried by the shaft 13 to which may be connected an eccentric strap which is, for example, pivoted to the member 17. Upon actuation of the shaft 13, as described, the effect of cam 14 and its engagement with the hook member 15 as described, is to actuate the plunger 22 toward the depression 24, and tending to extend the outer end of the plunger across the coin slot 10. During this actuating stroke, due to the movement of the bridge member 20, it will be obvious that the springs 23 will have been compressed to a certain extent. This compression serves to effect the return movement of the parts 17, 20, 22, etc., to their original, normal positions of rest.

Secured to the shaft 13, in the present example, is a bevel gear 30, arranged to mesh with an associated bevel gear 31 which may be disposed on a vertical, preferably stationary, stud shaft 32 arranged for the support of a journal or bearing 33 for the shaft 13. By preference, there is formed integrally with the bevel gear 31, a driving pinion 34, which in turn meshes with a similar pinion 35 for the purpose of rotating at least one of a pair of cam members such as 11, heretofore noted, and 36, both of which are disposed on a pivot shaft 37. The cams 11 and 36, together constitute a coin carrier, as will hereinafter appear, and it will be seen that this carrier, or one of its cam portions, upon being actuated by the gear 35, which operates responsively to the rotation of shaft 13, must always be operated in a predetermined timed

relation with the shaft 13 and its actuating handle.

As will be seen from Fig. 3, the cam members 11 and 36 are yieldingly positioned with their cam surfaces adjacent each other, by a coil spring 38 disposed between an enlargement or head on the pivot shaft 37, and the upper surface of the inside cam. In this manner the cams are yieldingly held adjacent each other, normally in the manner indicated by Fig. 3.

From Figs. 5 and 6, respectively, will be seen the nature and construction of the adjacently presented cam surfaces of the cam members 36 and 11. The innermost cam 11, which is tied to the gear 35, is provided with an external projecting flange 39, which extends peripherally beyond the adjacent margin of the cam 36, a sufficient distance so as to seal, at all times, any opening which may be created between the cams by the action of a deformed slug or other operating element. This flange extends, however, over only a portion of the circumference of the cam 11, as will appear from Fig. 6. Between the termini of this flange, the cam is provided with a depression 40, extending, say over a 90 degree sector of the inner surface of the cam, and disposed adjacent one of the lateral limits of the depression 40, is a pin 41, projecting outwardly beyond the inner surface of the cam, for a purpose hereinafter appearing. The cam 36 is provided with a depression 42, similar in scope and depth to the depression 40, except that the sector 42 includes a slope 43 extending between the depressed portion 42 and a normal or plane portion 44 of the cam 36. This plane portion 44 is again depressed, say over a sector of 60 degrees, to form a low point or area 45. Extending on each side of and between the low areas 42 and 45 is a groove 46, circular in form, and concentrically disposed on the cam. This groove serves as a runway or guide for the pin 41, when the cams are in assembled relation, for a purpose hereinafter appearing.

As will be noted, particularly from Fig. 5 et seq., the cam 36 is provided with a radially extending arm 47 which is normally adapted to impinge against a stationary portion 48 of the frame, and at other times adapted to impinge against a pin 49, also preferably disposed on the frame. These projections contact with the arm 47 to limit the angular movement of the cam 36, in the example shown, to substantially 45 degrees. It will be understood that the cam 36 is freely rotatable, between recited limits, about the pivot 37, and that any movement of this cam is effected solely by its frictional engagement, either directly with the cam 11, or with a coin between the cams; this frictional driving relation being maintained by the spring 38. As will appear from the drawings and later description, the carrier is entirely operative, even

though the cam 36 is stationary; the present provision for its limited movement being made to facilitate any necessary adjustment and clearing of the carrier.

5 The relation of the adjacent surfaces on the cams 11 and 36, and the timed driving relation between the gear 30 and the pinion 35, is such that until after the action of plunger 22 is completed, no coin receiving opening 10 is presented at the periphery of the carrier, adjacent the coin slot 10. However, immediately after the plunger has been brought to bear against the coin in slot 10, and is retracted to the position of Fig. 3 by springs 15 23, the depression 42 in cam 36 is open underneath the slot 10, (Fig. 7). In register with the depression 42, so as to effect an enlarged coin-receiving opening, is the depression 40 in cam 11. Immediately after this coin-receiving opening is brought adjacent the slot 10, the carrier receives the coin or slug by 20 gravity, and the cam 11 rotates clockwise, (Figs. 7 and 8), propelling the coin over a circular path, by means of the pin 41, normally traveling in the slot 46, and coacting with the flange 39. It may be noted that the cam 36 may or may not have been previously rotated counterclockwise, (Fig. 7). In either event, the first eighth revolution or so of the 25 cam 11 finds the cam 36 rotated by friction with the coin or slug, or with the cam 11 to the position indicated by Fig. 7, and positioned against further immediate clockwise rotation by engagement of the pin 47 with 30 projection 48.

The continued clockwise rotation of cam 11 carries the coin over the slope 43 on cam 36 and adjacent the plane surface thereof, (Fig. 8); the coin or slug at this point being pocketed within the depression 40 of cam 11, and 35 the depth of this depression being not substantially greater than the thickness, say of a five cent piece. In the case of a good coin, the coin will be discharged from the periphery of the carrier after it has rotated substantially 90 degrees, or until one of the boundaries or termini of the depression 40 comes to a position somewhat beyond the horizontal, so as to discharge the coin by 40 gravity into the usual coin-receiving slot 50 of the vending machine or the like with which the device is used, (Fig. 9). Since the depression 40 in cam 11 is of a depth corresponding to the thickness of a five cent piece 55 or other intended coin, there will be no appreciable friction preventing discharge of such coin, by gravity, into the coin slot. In the preceding description it will be understood that the continued use of good coins, 60 permits the cam 36 to remain stationary in the position shown in Fig. 5. The operation of the carrier as thus far described, has dealt with the passage therethrough of a normal, undistorted, undeflected coin, such as intended 65 to be deposited in the vending machine.

Considering now the action of a counterfeit coin or slug; when a relatively soft or thin piece of material is inserted in the slot 10 in lieu of a coin, the action of the plunger described above, pressing centrally of the slug, will form therein a diametral channel, bending the edges of the slug upwardly and away from its normal plane, thus obviously resulting in a greatly increased effective, or over-all thickness of the piece. Upon release of the plunger, the deformed slug will nevertheless fall into the enlarged aperture in the carrier, resulting from coincidence of the depressions 42 and 40, respectively, in the cams 36 and 11. The action of pin 41 is such as to force the deformed slug over the slope or shoulder 43 to a position upon or adjacent the plane surface 44, (Fig. 8). The increased effective thickness of the slug will, however, separate or spread the cams against the pressure of spring 38. Continued rotation of cam 11 will not, in this case, result in the discharge of the slug at a position in line with the coin-receiving slot of the vending machine, as shown in Fig. 9, but will retain 90 and carry the slug, by friction, to the point where the depression 40 of cam 11 comes into coincidence with the depression 45 in cam 36. This discharge position of a defective element will best be seen in Fig. 10.

From the preceding description, and a study of Figs. 7 to 10 inclusive, it will be obvious that the discharge of a defective, thin, or weak element, such as a slug, will be at a point substantially different than the point of discharge, say of a good five cent piece. The discharge of the slugs or counterfeits, may be effected into a separate receptacle or into the casing of the machine, so that the slug is obviously ineffective to operate the vending machine or like apparatus with which the present device is associated. The depending flange 39, described above, serves to prevent the receipt or discharge of either a slug or coin at other than the intended points; and at the same time guards against any unintended escape of either a coin or slug from the periphery of the carrier during its rotating movement. Obviously, the flange 39 serves as a cut-off to prevent more than one coin entering the carrier, at a time, and since the coin-receiving opening is not presented adjacent the slot 10 until after substantially a complete cycle of movement of the carrier, any tendency toward double charging of the carrier, is prevented.

It will be seen from the preceding description that the preferred embodiment of the invention is a machine of exceedingly simple and sturdy construction, that it consists of relatively few moving parts, and is characterized by the absence of small, expensive, machined portions, whereby the device may be produced in quantities at a reasonable cost. Trials and experiments with a machine con-

structed as described, indicate that it functions with absolute reliability in rejecting practically all of the usual types of slugs and counterfeit actuating elements, commonly employed to defraud vending machines and the like. A further noteworthy advantage, among others, is attained in the adjustment provision, and in the means for actuating the plunger 22, with a steady movement, thus obviating all danger of defacing standard coins.

I claim as my invention:

1. In a testing device for coins and like elements, means tending to deform the element under test, a receiver for the tested element, and means permitting expansion of the receiver responsive to the degree of deformation of the tested element.
2. In a testing device for coins and like elements, means tending to deform the element under test, means forming a receiving device for the tested element and adapted to deliver said element in locations predetermined according to the extent of deformation of the element.
3. In a testing device for coins and like elements, means tending to deform the element under test, a carrier for said element, and means, associated with the carrier, for determining the extent of travel of the element therein, according to the degree of deformation of the element.
4. In a testing device for coins and like elements, means tending to deform the element under test, means for receiving and carrying said element, and means associated with the carrying means, for determining the duration of retention in the carrier according to the extent of deformation of the element.
5. In a testing device for coins and like elements, means tending to deform the element under test, receiving and carrying means for said element including a pair of members having separable portions, and arranged to be moved relative to each other.
6. In a testing device for coins and like elements, means tending to deform the element under test, a coin carrier associated with the deforming means and including a pair of relatively movable members having adjacent cam surfaces adapted to sort the elements under test.
7. In a testing device for coins and like elements, means tending to deform the element under test, a coin carrier associated with the deforming means and including a pair of relatively rotatable members having adjacent surfaces, each of said surfaces having a coin receiving depression therein, and a projection on one of said members, adapted, upon rotation of said member, to impel the coin relative to the other member.
8. In a testing device for coins and like elements, means tending to deform the element under test, a coin carrier associated with the deforming means and including a
9. In a testing and sorting device for coins and like elements, the combination with means tending to deform the element under test, of a carrier including a pair of adjacently disposed, relatively rotatable members, each having a coin receiving depression adjacent the other member, and means for rotating one of said members to effect coincidence of said depressions, whereby to effect discharge of a deformed coin or like element.
10. In a testing device for coins and like elements, means tending to deform the element under test, a carrier disposed to receive the element from said deforming means, said carrier comprising a pair of relatively rotatable members, one of said members having a depression adapted to accommodate a coin of normal proportions, a peripheral projection on one of said members, interrupted to form a marginal coin opening adjacent said depression, and means for rotating one of said members in timed relation with the actuation of said deforming means.
11. In a testing and sorting device for coins and like elements, receiving and holding means for the element under test, a member adapted to be brought into engagement with the element under test, means for subjecting the element to a steady pressure through said member, a rotatable carrier for the element under test, means for operating the carrier in timed relation with the engaging member, and means associated with the carrier for determining the extent of travel of the element therein, according to the degree of deformation of the element.
12. In a device for testing and sorting coins and like elements, coin receiving and holding means, a plunger adapted to be brought into engagement with the element under test, means for subjecting the element to a steady pressure applied through said plunger, a carrying and sorting device adapted to receive said element, and including a pair of relatively rotatable members, each having a depression adjacent the other member, and means for rotating one of said members in timed relation with the actuation of said deforming means.

THOMAS W. MILTON.
